UNITED STATES PATENT OFFICE.

JAMES L. RILEY, OF PHILADELPHIA, PENNSYLVANIA.

DESIGN FOR A STEAM-GENERATOR SECTION.

SPECIFICATION forming part of Design No. 27,215, dated June 15, 1897.

Application filed April 30, 1897. Serial No. 634,652. Term of patent 7 years.

To all whom it may concern:

Be it known that I, JAMES L. RILEY, a citizen of the United States, residing in the city and county of Philadelphia, in the State of Pennsylvania, have invented and produced a new and original Design for Steam Generator Sections, of which the following is a specification, reference being had to the accompanying drawings forming part thereof.

My invention relates to and comprehends a design for a generator section adapted for employment as the end section of a steam generator composed of a number of assembled sections.

15 In the drawings,

Figure 1 is a view in side elevation of said section looking toward the outer wall of the same.

Figure 2 is a vertical, sectional, elevation taken on the line 2—2 of Figures 1 and 4.

Figure 3 is a sectional plan taken on the line 3—3 of Figures 1 and 4.

Figure 4 is a view in side elevation of said section, looking toward the inner wall of the same.

As shown in the drawings, the leading and principal feature of my design consists of a section having its outer wall A formed with a continuous concavo-convex projection, a, 30 extending along its top and down its front and rear edge,—and with a central rectangular panel a',—and having its inner wall, B, formed with a concavo-convex projection, b,

extending, in line with the concavo-convex projection a, along the top of said wall B, 35 and down along its rear edge, and part of the distance down its front edge, the body of the remaining portion of the wall B, which exists in a plane considerably inside or below that of the top of said concavo-convex projection, 40 b, being, however, formed with concavo-convex ribs or projections c, c' extending, from the vertical portions of the concavo-convex projection b referred to, and into which they merge, across the face of said wall, the rib or 45 projection c nearly to the front edge of the section, and the rib or projection c' nearly to the rear edge of the section.

d is a bead upon the crest and following the course of the concavo-convex projection b. 50

e is a transverse channel formed in the concavo-convex projection b at the rear of the section, and f is a transverse channel formed in said projection at the front of the section.

Having thus described my invention, what 55 I claim, and desire to secure by Letters Patent, is—

The design for a steam generator herein shown and described.

In testimony that I claim the foregoing as 60 my invention I have hereunto signed my name this 22d day of April, A. D. 1897.

JAMES L. RILEY.

In presence of—

F. NORMAN DIXON,
THOS. K. LANCASTER.
